ADVERTISING SIGN

Hy C. Hammer, Chicago, Ill., assignor to Hammer Brothers, Incorporated, Chicago, Ill., a corporation of Illinois

Application August 9, 1949, Serial No. 4,372

Term of patent 14 years

(Cl. D1—12)

To all whom it may concern:

Be it known that I, Hy C. Hammer, a citizen of the United States, residing at Chicago, county of Cook, and State of Illinois, have invented a new, original, and ornamental Design for an Advertising Sign, of which the following is a specification, reference being had to the accompanying drawing, which forms a part hereof, in which Figure 1 is a front elevational view of an advertising sign embodying my design; Fig. 2, a plan view of the same; Fig. 3, a rear elevational view; Fig. 4, a side elevational view taken from the right side of Fig. 1; and Fig. 5, a side elevational view taken from the left side thereof.

I claim:

The ornamental design for an advertising sign, as shown.

HY C. HAMMER.
